UNITED STATES PATENT OFFICE

STANLEY W. NICHOLSON, OF TOLEDO, OHIO, ASSIGNOR TO THE LOCLIF COMPANY, OF TOLEDO, OHIO

LATCH-RETRACTING ATTACHMENT FOR WINDOW-OPERATING DEVICES

Application filed February 16, 1928. Serial No. 254,827.

The invention relates to a device for retracting the bolt of a door lock to be applied as an attachment to any of the standard forms of window operating devices for automobiles, 5 the attachment being so coordinated with the rotary shaft of the window operating devices as to admit of the latching bolt being withdrawn, when desired, by the same handle which actuates the window operating device.

10 The invention is illustrated in the accompanying drawings, in which:—

Fig. 1 is a front elevation of an automobile door frame provided with a standard window actuating device, which latter is equipped 15 with the bolt retracting attachment.

Fig. 2 is an enlarged fragmentary horizontal section.

Fig. 3 is a front sectional elevation of the attachment and the actuating shaft of the 20 window operating device, the parts of the attachment being in inoperative relation.

Fig. 4 is a similar view showing the parts in proper relation to retract the bolt.

Fig. 5 is an exploded view of the attachment showing the various elements in perspective.

Fig. 6 is a sectional side elevation of the pawl carrying element.

Referring to Figs. 1 and 2, 1 indicates the 30 frame of an automobile door, provided with the usual sliding glass or window element 2 adapted to be raised and lowered in slots formed in the stiles of the door frame, by means of any of the standard operating devices involving gearing actuated by a rotary crank or handle, the operating mechanism being mounted upon a cross panel 3 secured to the door stiles. The particular form of window operating mechanism, illustrated 35 40 45 50

serves as a counterbalance for the weight of the glass and assists in the raising or closing movement of the latter. The inner end of the shaft 7 is provided with a crank handle 13, which is rotated in one direction to raise 55 the window element and in the opposite direction to lower the same, said shaft preferably being substantially square in cross section.

Loosely mounted on the shaft 7 is a casing 60 comprising an outer cup-like member 20 having an enlarged central opening 20' and having secured to the outer surface of its peripheral rim a bracket 21 carrying a pin 22, the cooperating casing member comprising 65 a cup-like member 30 having a peripheral rim fitting within the rim of the cup member 20, said rim being provided with corrugations 31, which constitute ratchet teeth, and to the outer surface of which the 70 rim of member 30 may be secured by crimping the latter into locking engagement. The central portion of the member 30 is formed with a concave depression 32 having a round opening 33 in the center thereof through 75 which the squared shaft 7 passes freely.

Within the casing is a generally disk-shaped element 34 having an enlarged central opening 37 and an arcuate recess 35 in its peripheral edge, the opposite faces of the 80 disk having shallow lozenge-shaped depressions 36, 36' therein.

Pivottally mounted in the central opening 37 in the plate or disk 34 is a pawl carrier, which is capable of a slight rotary movement 85 relative to the plate 34, as will be explained hereinafter, said pawl carrier, comprising an arm 37 having a concave boss 38 provided with a generally squared central opening 39, which fits over the drive shaft 7 of the window operating device, the hollow boss fitting the depression 32 in the center of the casing member 30, when the parts are assembled. A similar arm 37' is provided with a similar shaped boss 38' having a squared central 90 opening 39', the boss 38' telescoping with or nesting in the boss 38, so that the openings 39, 39' are in registry and are both engaged by the shaft 7. Pivoted between the upper 95 ends of the arms 37 and 37' by a stud 40 is 100

a generally arc shaped pawl 42, which fits in the arcuate recess 35 in the edge of the plate or disk 34, and is provided with rounded ends to cooperate with the corrugations 31 on the casing. Mounted on the pivot 40 is a friction plate 42, which engages one side of the pawl 41 and serves to hold the same in its various positions of adjustment.

Connected to the pin 22 carried by the 10 casing member 20 is a link or bar 24, which is connected by a pivot pin 26 to the inner end of the latching bolt 25 of the automobile door lock, which bolt, as is usual in devices of this kind, is normally held in latching position by a spring.

The two members of the casing and the 20 two supporting cupped arms of the pawl carrier are preferably made of sheet metal stampings, which insures sufficiently accurate engaging fits between the respective parts without requiring said parts to be milled or otherwise expensively finished.

When the parts of the attachment are assembled, the casing members 20 and 30 are 25 in telescoping engagement, and are locked together preferably by crimping the flange of member 20 into the corrugations of member 30, either in whole or in part. The squared shaft 7 of the window operating 30 mechanism engaging the squared holes 39 and 39' in the pawl carrier will rotate said pawl carrier and the plate or disk 34, when said shaft 7 is actuated by the crank handle 13, the rotary motion being communicated to the disk 34 by reason of the frictional engagement of the pawl carrying elements therewith, as well as the engagement of the pawl 41 with the arcuate slot 35 in said disk. A steady rotary movement 40 of the handle 13, if gradually applied, will cause a corresponding movement of the pawl carrier, the pawl and the disk 34, as the disk 34, which has considerable weight and inertia, will take up the rotary movement of the 45 shaft 7 when gradually applied, but, if the initial movement of said shaft be accelerated, the inertia of the disk 34 will cause the latter to lag behind in this rotary movement, so that the pawl carrier will move relatively 50 to the disk and cause the pawl to slide in the arcuate recess 35, so that the end of the pawl, which projects in the direction of movement of the carrier, will be forced into engagement with one of the corrugations or teeth on the 55 rim of the inner casing member 30, thereby causing the casing to rotate with the pawl carrier, the disk 34 and the shaft 7, thereby exerting a pull on the link 24 sufficient to retract the latch bolt 25 of the lock. It will be 60 noted that the pin 22 carried by the outer casing member is so disposed that a partial rotation of the casing in either direction will retract the bolt 25. After the bolt 25 has been retracted, and the handle released, the 65 spring in the lock will immediately return

the bolt to its normal projected position, thereby rotating the casing in the opposite direction to its initial or normal position, and restore the pawl to a neutral position.

From the foregoing description, it is apparent that the attachment is capable of ready application to a standard window operating mechanism having a rotary shaft with which the pawl carrier of the attachment may be engaged to partake of any rotary movement of the shaft and that, if the shaft be rotated at a steady and uniform rate, the only effect of such rotation will be to raise or lower the window element as the case may be, but, if the shaft be given an accelerated initial movement, the pawl carrier will participate in the accelerated movement and therefore move faster than the weighted disk 34 and one end of the pawl will be thrown into engagement with the ratchet teeth 31 on the casing, causing the latter to participate in the rotary movement of the handle, which actuates the link 24, thereby retracting the bolt 25 and permitting the door to be opened, whereupon, the release of the handle will permit the spring which actuates the latching bolt to restore the parts to normal position. It will be understood that there is a certain lost motion between the shaft 7, pinion 6, and gear 9, of the window operating device, and that, since it is necessary to move the bar 24 only a small fraction of an inch to unlatch the door, such lost motion is sufficient to permit the initial accelerated rotation of the shaft and effect an operation of the latch without vertical movement of the window.

What I claim is:

1. A door latch retracting attachment for a window operating device, comprising a rotary casing connected to the latch, means actuated by a sudden acceleration of the prime mover of the window operating means for operatively connecting the casing with said operating means to actuate the latch.

2. A door latch retracting attachment for a window operating device which device includes a rotary shaft, comprising a casing loose on said shaft and connected to the latch, and means actuated by a sudden acceleration of said rotary shaft for operatively connecting the casing to said shaft to actuate the latch.

3. A door latch retracting attachment for a window operating device which device includes a rotary shaft, comprising a casing loose on said shaft and connected to the latch, a ratchet on the casing, a pawl carried by said shaft for rotation therewith, and means loosely surrounding the shaft normally holding the pawl out of engagement with the ratchet and effective to engage the pawl with the ratchet upon a sudden acceleration of the shaft.

4. A door latch retracting attachment for a window operating device which device in-

cludes a rotary shaft, comprising a casing loose on said shaft and connected to the latch, a ratchet on the casing, a carrier on said shaft and rotatable therewith, a pawl pivoted to said carrier, and a disk loosely surrounding the shaft having a peripheral notch engaged by the pawl; whereby a sudden acceleration of the shaft will cause the pawl to slide in said notch and engage the ratchet and 10 impart rotary motion to the casing.

5. A door latch retracting attachment for a window operating device which device includes a rotary shaft, comprising a casing including an outer cup and an inner cup having a ratchet rim locked to the rim of the outer cup, both cups loosely surrounding the rotary shaft, a link connection between the casing and the latch, a disk within the casing rotatable with respect to said shaft and having an arcuate notch in its peripheral edge, a pawl carrier mounted on said shaft for rotation therewith, and an arc-shaped pawl pivoted to said carrier and engaging the notch in said disk and normally held out of 20 engagement with the ratchet rim of the inner cup and slidable in said notch to engage the ratchet upon a sudden acceleration of the shaft.

6. A door latch retracting attachment for 30 a window operating device which device includes a rotary shaft, comprising a casing including an outer cup and an inner cup having a ratchet rim locked to the rim of the outer cup, both cups loosely surrounding 35 the rotary shaft, a link connection between the casing and the latch, a disk within the casing rotatable with respect to said shaft and having an arcuate notch in its peripheral edge, a pawl carrier mounted on said shaft 40 for rotation therewith, and a double ended arc-shaped pawl pivoted to said carrier and engaging the notch in said disk and normally held out of engagement with the ratchet rim of the inner cup and slidable in said notch 45 to engage the ratchet upon a sudden acceleration of the shaft.

In testimony whereof I affix my signature.
STANLEY W. NICHOLSON.
